UNITED STATES PATENT OFFICE.

JAMES O. HANDY, OF PITTSBURGH, PENNSYLVANIA, ASSIGNOR TO PITTSBURGH TESTING LABORATORY, OF PITTSBURGH, PENNSYLVANIA, A CORPORATION OF PENNSYLVANIA.

METHOD OF TREATING WOOL-GREASE.

1,194,015.

Specification of Letters Patent

Patented Aug. 8, 1916.

No Drawing.

Application filed April 22, 1916. Serial No. 92,845.

To all whom it may concern:

Be it known that I, JAMES O. HANDY, a citizen of the United States, residing at Pittsburgh, Allegheny county, Pennsylvania, have invented a new and useful Method of Treating Wool-Grease, of which the following is a full, clear, and exact description.

My invention has relation to the art of refining wool grease, and more particularly to a method of bleaching either the neutral grease, after the fatty acids have been removed therefrom, or the bleaching of the raw grease. This neutral grease may be produced by any of the known methods, or preferably by one of the methods described and claimed in the copending applications of myself and Robert M. Isham, Serial No. 92,842, filed April 22, 1916, and Serial No. 92,843, filed April 22, 1916. The neutral grease produced by any of these methods requires bleaching in order to produce the final desired commercial product.

The use of fullers' earth as a bleaching agent for greases has long been known, but it has not heretofore been possible to produce the desired results by the use of this clay in bleaching wool grease. I have discovered that if the grease is dissolved in a suitable solvent, such as petrolic ether, and the solution is then agitated with fullers' earth, a bleaching effect can be produced which cannot be obtained by treatment of the grease alone with fullers' earth.

In carrying out my invention I form a solution of the grease in the solvent, preferably petrolic ether, approximately one gallon per pound of grease, and then agitate the solution in a suitable vessel with fullers' earth, using an amount of earth approximately equal in weight to the weight of the grease. The fullers' earth acts by adsorption, and is peculiarly effective when the grease is in solution. After the earth is precipitated or settled out of the solution, the latter is then distilled and the grease recovered. The petroleum odors can be removed from the grease by blowing with air or other suitable gas at reduced pressure at a temperature of from 90 degrees to 100 degrees centigrade.

Where water has been used in the production of the grease for the purpose of washing therefrom the soap produced by the saponification of the free fatty acids, I eliminate this water by adding petrolic

ether, preferably of about 110 degrees C. boiling point, and distilling up to a temperature where the water will pass over with the solvent. The grease is then cooled and is again dissolved in petrolic ether preparatory to the bleaching.

Instead of disposing of the water by distillation of the wet grease before bleaching, the fullers' earth may be added in sufficient quantity to absorb the water. The mixture of grease and fullers' earth is then heated in pans in a drying oven at a temperature preferably of from 100 degrees to 110 degrees C. The dry material is then agitated with petrolic ether and filtered. In either case, the grease may be recovered from the petrolic ether solution by distilling off the solvent. The petrolic ether is then ready for further use. By the term "petrolic ether" as used herein and in the appended claims, I intend to include naphtha, gasoline, and all similar petroleum products having a sufficiently low boiling point. The boiling point should not be sufficiently low to cause losses, and, on the other hand, it should not be sufficiently high to give undesirable residual products under the conditions of evaporation employed. In practice I have found a boiling point of from 70 degrees to 100 degrees C., and preferably between 80 degrees and 100 degrees C., to give good results.

My invention is also applicable to the treatment and bleaching of raw grease after its extraction from the wool. In such cases, the method of treatment is substantially the same as that before described. A solution of the raw grease in petrolic ether is made, and this solution is agitated with fullers' earth. This preliminary bleaching may in some cases replace the final bleaching, and in any case, renders the final bleaching more easily carried out.

I claim:

1. In the art of treating wool grease, the method of bleaching which comprises forming a solution of the grease in a solvent, and then agitating the solution with fullers' earth, substantially as described. 100
2. In the art of treating wool grease, the method of bleaching which comprises forming a solution of the grease in petrolic ether, and then agitating the solution with fullers' earth, substantially as described. 105
3. In the art of treating wool grease, the method which comprises drying the grease, 110

then forming a solution in a suitable solvent and then agitating the solution with fullers' earth, substantially as described.

4. In the art of treating wool grease, the method which comprises drying the grease, then forming a solution in petrolic ether and then agitating the solution with fullers' earth, substantially as described.

5. In the art of treating wool grease, the method which comprises drying the grease, then forming a solution in petrolic ether, then agitating the solution with fullers' earth, and then distilling off the solvent and recovering the grease, substantially as described.

6. In the art of treating wool grease, the method which comprises drying the wet grease by adding sufficient fullers' earth thereto to absorb the water, then heating, and then agitating the dried material with petrolic ether until the grease is dissolved and bleached, substantially as described.

7. In the art of treating wool grease, the method of bleaching which comprises form-

ing a solution of the neutral grease in petrolic ether in the proportion of about one gallon of petrolic ether to each one pound of grease, and then agitating the solution with fullers' earth, substantially as described.

8. In the art of treating wool grease, the method of bleaching which comprises forming a solution of the neutral grease in a solvent, and then agitating the solution with an absorbent material capable of bleaching the wool grease contained in the solvent substantially as described.

9. In the art of treating wool grease, the method which comprises making a solution of the raw grease in petrolic ether, and agitating with fullers' earth, substantially as described.

In testimony whereof, I have hereunto set my hand.

JAMES O. HANDY.

then forming a solution in a suitable solvent and then agitating the solution with fullers' earth, substantially as described.

4. In the art of treating wool grease, the method which comprises drying the grease, then forming a solution in petrolic ether and then agitating the solution with fullers' earth, substantially as described.

5. In the art of treating wool grease, the method which comprises drying the grease, then forming a solution in petrolic ether, then agitating the solution with fullers' earth, and then distilling off the solvent and recovering the grease, substantially as described.

6. In the art of treating wool grease, the method which comprises drying the wet grease by adding sufficient fullers' earth thereto to absorb the water, then heating, and then agitating the dried material with petrolic ether until the grease is dissolved and bleached, substantially as described.

7. In the art of treating wool grease, the method of bleaching which comprises form-

ing a solution of the neutral grease in petrolic ether in the proportion of about one gallon of petrolic ether to each one pound of grease, and then agitating the solution with fullers' earth, substantially as described.

8. In the art of treating wool grease, the method of bleaching which comprises forming a solution of the neutral grease in a solvent, and then agitating the solution with an absorbent material capable of bleaching the wool grease contained in the solvent substantially as described.

9. In the art of treating wool grease, the method which comprises making a solution of the raw grease in petrolic ether, and agitating with fullers' earth, substantially as described.

In testimony whereof, I have hereunto set my hand.

JAMES O. HANDY.

Correction in Letters Patent No. 1,194,015.

It is hereby certified that in Letters Patent No. 1,194,015, granted August 8, 1916, upon the application of James O. Handy, of Pittsburgh, Pennsylvania, for an improvement in "Methods of Treating Wool-Grease," an error appears in the printed specification requiring correction as follows: Page 2, line 35, claim 8, for the word "absorbent" read *adsorbent*; and that the said Letters Patent should be read with this correction therein that the same may conform to the record of the case in the Patent Office.

Signed and sealed this 21st day of November, A. D., 1916.

[SEAL.]

Cl. 87—26.

F. W. H. CLAY,

Acting Commissioner of Patents.
